UNITED STATES PATENT OFFICE.

ROBERT C. BECK, OF BROOKLYN, NEW YORK, ASSIGNOR TO THE CUTLER-HAMMER MFG. CO., OF MILWAUKEE, WISCONSIN, A CORPORATION OF WISCONSIN.

OIL-WELL HEATER.

Application filed February 28, 1921. Serial No. 448,478.

To all whom it may concern:

Be it known that I, ROBERT C. BECK, a citizen of the United States, residing at Brooklyn, in the county of New York and State of New York, have invented new and useful Improvements in Oil-Well Heaters, of which the following is a specification.

This invention relates to an oil well heater. The oil well heater to which this invention is particularly applicable comprises, in general, a plurality of electric heaters enclosed in protective casings rigidly fastened to heads within which connections may be made between the heaters and to a source of current supply.

Such a heater is particularly suitable for insertion in an oil well so as to heat the bottom thereof to increase the flow of oil therefrom.

Among the objects of the invention is to provide an efficient and durable oil well heater which may be readily and economically manufactured.

Another object is to provide an electric heating appliance composed of a number of electric heaters connected in groups and arranged so that any group of heaters or any heater of a particular group may readily be removed and replaced without interfering with the other groups or the other heaters of a particular group.

Another object is to provide a heater which when lowered into an oil well will not be adversely affected by oils or salt water.

Another object is to provide an oil well heater mechanically enclosed and protected from the elements of the earth.

Another object is to provide a protective casing for an oil well heater which will not be affected by temperature changes.

Another object is to provide an oil well heater of great heating capacity.

Other objects and advantages will herein-after appear.

The views of the drawings are:

Fig. 1 shows an oil well heater, partly in section.

Fig. 2 is an enlarged elevation, partly in section, of the upper terminal housing.

Fig. 3 is an enlarged elevation, partly in section of the lower terminal housing.

Fig. 4 is an enlarged vertical section through one of the casings showing two electric heaters joined end to end.

Fig. 5 is an enlarged elevation of a portion of the heater showing the casings held in spaced relation by a retaining ring.

Fig. 6 is a horizontal section on line 6—6 of Fig. 5.

Fig. 7 is a top plan of a heater.

Fig. 8 is a horizontal section on line 8—8 of Fig. 2.

Fig. 9 is a horizontal section on line 9—9 of Fig. 3.

Fig. 10 is a perspective of the cable clamps shown in Fig. 2.

The oil well heater comprises a plurality of electric heaters 1 having tubular jackets enclosed within tubes or casings 2, which terminate in and are fastened to upper and lower terminal housings 3 and 4.

Each electric heater comprises in general an elongated tubular jacket 5, plug terminals 6, one inserted in each end of the jacket 5 and rigidly fastened thereto, a helical ductile resistor 7 arranged within the jacket and connected to the plug terminals, and insulation 8 compacted within the jacket and around the resistor.

The casings 2 surrounding the heaters are fastened to the terminal housings 3 and 4 by welding or other suitable means.

The terminal housings 3 and 4 each have a base 9 within which is seated an insulating block or disc 11. The terminals of the electric heaters extend through the housing bases 9 and are fastened to the insulating discs by nuts 12. The electric heaters terminating in the housing may be connected in series or in any other desired manner by suitable straps or connectors 13.

The upper terminal housing 3 is provided with a cap 10.

Between the cap 10 and the base 9 is a metal disc 25 provided with an annular groove on each side to receive a round gasket 17, to prevent ingress of moisture to the terminal chambers.

The cap and base are fastened together by machine screws 16.

In the disc 25 there is welded or brazed a plurality of insulated sleeves or tubes 5 26. Inside each tube is compressible water-

tight insulation 27, such as gutta percha or the like, and the insulation and tube are swaged tight to a stud 29 which is threaded at both ends to receive nuts 32.

10 A washer 28 of insulating material prevents the nuts 32 from being screwed down against the tube 26 and grounding the same.

Flexible conductors 33 connect the insulated studs 29 to heater terminals.

Inside the cap 10, and screwed or clamped to the top thereof, are two blocks 30 of insulating material having threaded holes extending therethrough. When these blocks 20 are screwed together and to the top of the cap 10, the threads in the holes grip the insulation on the cable conductors 34 and relieve the strain from the terminals, should tension be applied to the conductors 34 exterior of the housing.

The cable conductors 34 extend through the insulating blocks 30 and are connected to the studs 29.

In the top of the cap 10 are two water 30 tight metal glands or bushings 19 which are tapered on the inside and when screwed into position compress insulating packing 31 to form a water tight joint.

A cable ring 18 is fastened to the top of 35 the cap 10 for supporting the oil well heater and enabling it to be lowered into and withdrawn from an oil well.

The lower terminal housing 4 is provided 40 with a cone-shaped nose 15, so that it will readily penetrate the heavy oil and sand in the bottom of the oil well.

The base 9 and nose 15 of the terminal housing 4 are fastened together by means of machine screws 16, and are provided with 45 a seal or gasket 17 therebetween to prevent ingress of moisture to the terminal chamber.

An oil well heater of any desired length 50 may be provided by joining a plurality of electric heaters end to end, as shown in Fig. 4. The electric heaters 1 may be joined end to end by a metallic conducting sleeve 20 screwed or otherwise fastened to the plug terminals 6. The sleeve connector 20 may be surrounded by a tube or tubes of mica 21 or other suitable insulating material.

The electric heaters may be of the form disclosed in Patent 1,359,400, dated November 16, 1920.

The plug terminals 6 may be of the form 60 disclosed in co-pending application, Serial No. 437,792, filed January 17, 1921.

The connector for connecting the tubular heaters end to end may also be of the form disclosed in the aforesaid co-pending application.

The casings 2 may be provided with retaining rings 24 intermediate the terminal housings, to mechanically strengthen the heater and hold the casings in definite spaced relation.

70 The oil well heater is so constructed and assembled that any group of electric heaters or the heaters within any casing may be readily removed and another group of heaters inserted therein without interfering with the heaters enclosed within the other casings. Furthermore, the electric heaters within each casing are so connected to one another that any heater of a particular group may be readily removed, another tubular 80 heater inserted in its place and the entire group replaced within the casing without interfering with the other heaters of the particular group.

In pumping oil and petroleum from oil 85 wells it is comparatively simple to pump the thin or lighter oils which flow freely and seep through the strata and pores of the earth easily. With the thick or heavier oils, however, there is a tendency for the oil to 90 seal or clog the pores in the earth or oil sands and it is imperative that some simple and efficacious means be provided to open the clogged pores in order that the oil may be pumped to the surface. A heater of the 95 type herein described may be lowered to the bottom and into the sands of an oil well to heat the oil and open the clogged pores whereby the oil may be readily drawn from the strata or oil sands.

100 While but one embodiment has been shown and described various other embodiments and adaptations may be made of the invention contained herein.

The invention claimed is:

1. An oil well heater comprising a plurality of electric heaters arranged in groups, protective casings therefor, and means whereby any group of heaters may be removed without interfering with the other 110 groups of heaters.

2. An oil well heater comprising a plurality of electric heaters arranged in groups, a protective casing for each group of heaters, and means whereby any group of heaters 115 may be removed from its respective casing without interfering with the other groups of heaters.

3. An oil well heater comprising a plurality of electric heaters arranged in groups, protective casings therefor, and means whereby any group of heaters may be removed and a particular heater of the removed group replaced without interfering with the other heaters.

4. An electric heater for an oil well having a plurality of groups of heaters electrically connected and mechanically separated and held in spaced relation to one another.

5. In combination, a plurality of elongated casings rigidly fastened together by terminal housings, electric heaters having tubular jackets within the casings, and means 40 to electrically connect the heaters within one casing to the heaters within another casing.
6. A heater for an oil well having an elongated casing, a housing rigidly fastened 10 to each end of the elongated casing, an electric heater within the casing, and an insulating disc in each housing for attaching the electric heater thereto.
7. An oil well heater having a plurality 15 of casings separated from one another and held in definite fixed relation by terminal housings, electric heaters within each casing joined end to end, and means within each terminal housing to join the heaters 20 electrically.
8. An electric heater for an oil well comprising a plurality of elongated casings fastened to terminal housings, electric heaters with the casings spaced from the walls 25 thereof, and means within each terminal housing for supporting the electric heaters.
9. An electric heater for oil wells comprising an elongated casing, housings attached to each end thereof, an insulating 30 block within each housing, electric heaters within the elongated casing attached to the insulating block, and heater connecting leads extending through one of the housings to connect the electric heaters.
- 35 10. In combination an electric heater comprising a plurality of protective casings substantially parallel to one another and rigidly held at the ends thereof, means intermediate the ends to hold them in definite spaced relation to one another, and electric 40 heaters enclosed within the casings, the heaters of the several casings being connected electrically.
11. An oil well heater comprising a plurality of tubular casings, electric heaters 45 within each casing, the heaters of the several casings being joined electrically, and terminal housings rigidly fastened to the ends of the casings, one of said housings being provided with a cone-shaped nose. 50
12. An oil well heater comprising a plurality of tubular casings, electric heaters within each casing, the heaters of the several casings being joined electrically, and terminal housings rigidly fastened to the 55 ends of the casings, one of said housings being provided with a cable attaching means.
13. In combination a plurality of heater protective casings rigidly fastened to a terminal housing having a base and cap therefor, an insulating member mounted in the housing base, electric heaters fastened to the insulating member, and means to seal the housing against ingress of moisture. 60
14. In combination a plurality of elongated protective casings rigidly fastened to a terminal housing, an insulating disc seated in the terminal housing, and electric heaters fastened to the insulating disc and insulated 65 from the terminal housing. 70

In witness whereof, I have hereunto subscribed my name.

ROBERT C. BECK.
